PISTON AND PACKING THEREFOR

Sven T. Nelson, Michigan City, Ind.

Application October 28, 1933, Serial No. 695,565

3 Claims. (Cl. 309—22)

This invention relates to packings of the type employed in motors and pumps of the reciprocating piston type to effect tight joints between the contacting walls of the cylinders and pistons. 5 The present invention has been designed for a type of motor or pump disclosed in my co-pending application for Pump and motor structures, Serial No. 614,082, filed May 28, 1932, wherein the pistons and cylinders, or, more properly speaking, the piston chambers, are of rectangular cross section, and the ends of the piston chambers are closed by removable walls. In the structure of the aforesaid application the side and end walls of the piston, and also the side and end walls of the cylinder or piston chamber are formed with grooves, and these grooves are filled with packing comprising straight packing strips for the side and end walls cooperating with L-shaped corner packing strips, and independent 15 bow springs underlying the packing strips to force the same outwardly into snug sliding contact with the opposing walls.

The primary object of the present invention is to provide an improved packing, which will afford a better seal at the corners.

A further object is to provide an improved spring backing which may also be removed and replaced as a unit.

Still other objects and attendant advantages 30 of the invention will be apparent to persons familiar with the art from the following detailed description, taken in connection with the accompanying drawing, wherein I have illustrated one simple and practical embodiment of the invention, 35 and in which—

Fig. 1 is a side elevation of the upper portion of a rectangular piston or plunger, showing my improved packing therein, with the end walls of the piston chamber fragmentarily shown.

40 Fig. 2 is a similar view to Fig. 1, but with the packing strip removed to disclose the underlying spring backing.

Fig. 3 is an end elevation of the upper portion of the piston or plunger, with the side walls 45 of the piston chamber fragmentarily shown, and also showing packing strips in such side walls engaged with the sides of the piston or plunger.

Fig. 4 is an enlarged sectional plan view on the line 4—4 of Fig. 1.

50 Fig. 5 is an enlarged sectional plan view on the line 5—5 of Fig. 1.

Fig. 6 is a view similar to Fig. 5, showing the main side and end packing strips and their spring 55 backing members meeting in a miter joint.

Referring to the drawing, 10 designates as an entirety a rectangular piston body, herein shown as of greater length than width, but, so far as the present invention is concerned, the same may be square. The side and end walls of the body 10 are formed with grooves or channels 11 that register with each other at their ends. On the bottom wall of each groove is a spring backing for the packing strips, the same preferably consisting of comparatively thin flat metal strips 12, to the outer surface of which are riveted or otherwise attached at one end a series of bow springs 13. Bearing against the springs 13 are the packing strips, each preferably of sectional structure, as shown, comprising, in the preferred 15 form, upper and lower sections 14 and 15 formed at their ends with inter-engaging hooks 14' and 15', respectively, whereby the several sections are connected endwise throughout the full length of the strip. To prevent the sections from falling 20 apart when the strip is removed, I also preferably permanently connect them as by means of a rod or wire 16 extending through the hook portions of all the sections and riveted at its ends against the outer end walls of the end sections. To facilitate the removal and replacement of the 25 packing strips, the end sections of the strips are formed with tapped holes 17, so that, upon the removal of an end wall of the piston chamber, a suitable tool with a threaded end can be screwed 30 into one of the holes 17, and the strip thus withdrawn. Similarly, by gripping an end of the backing strip 12 by a pair of pinchers, this may 35 also be withdrawn.

Since the side and end grooves 11 are in the same transverse plane of the piston body, and register with each other at their ends, one opposed pair of packings (the side packings as herein shown) are made of full length, while the other opposed pair are shortened by the depth 40 of the two grooves, so that the end portions of one opposed pair overlap the ends of the other opposed pair, as clearly shown in Fig. 4. While I have shown the side packings as overlapping the ends of the end packings, this might, of course, 45 be reversed.

Instead of arranging the packings with the end portions of one pair overlapping the ends of the other pair, as above described, I may extend all the packing and backing strips the full length 50 of their respective grooves, and bevel their ends, as shown at 14a and 12a in Fig. 6, so as to form miter corner joints.

In order to afford a suitable packing of the corner portions of the piston body, I form in such 55

corners, preferably just below registering corners of the grooves 11 oblique corner grooves 18, most clearly shown in Fig. 5, and in these grooves are disposed corner blocks 19, preferably of the triangular form illustrated, and formed with rectangular wear surfaces 19'. To provide a suitable spring backing for these corner blocks, I preferably attach to the oblique edge of each block a bow spring 20, the free ends of the spring bearing on the bottom wall of the groove 18. The blocks 19 are of a size such that their end portions lap the end portions of the main side and end packing strips, as clearly shown in Fig. 4, whereby the corner portions as well as the sides and ends of the piston body are fully sealed against the side and end walls of the piston chamber.

As indicated in Fig. 3, the walls of both the piston body and the piston chamber are preferably equipped with packing of the type above described located in spaced relation, so as to form a double seal, but this, of course, is optional.

I have herein shown and described a form of the invention which in practice has been found to satisfactorily effectuate the stated purposes and objects thereof; but obviously changes may be made in the details without departure from the scope of the invention as defined in the claims.

I claim:

30. 1. The combination with a rectangular piston body formed with side and corner grooves, of packing therefor, comprising straight packing

strips occupying said side grooves, spring backings in said side grooves behind said strips, corner blocks occupying said corner grooves and formed with rectangular wear surfaces, and individual spring backings in said corner grooves behind said corner blocks. 5

2. The combination with a rectangular piston body formed with side grooves registering with each other at the corners of the piston body and with corner grooves laterally offset from said side grooves, of straight packing strips occupying said side grooves with the end portions of one pair of opposed strips overlapping the ends of the other pair of opposed strips, spring backings in said side grooves behind said strips, corner 10 packing blocks occupying said corner grooves and formed with rectangular wear surfaces, and individual spring backings in said corner grooves behind said corner blocks. 15

3. The combination with a rectangular piston body formed with side grooves registering with each other at the corners of the piston body and with corner grooves laterally offset from said side grooves, of straight packing strips occupying said side grooves and formed with oblique 20 ends meeting in miter joints, spring backings in said side grooves behind said strips, corner packing blocks occupying said corner grooves and formed with rectangular wear surfaces, and individual spring backings in said corner grooves 25 behind said corner blocks. 30

SVEN T. NELSON.
